UNITED STATES PATENT OFFICE.

LOUIS T. EANES, OF SELMA, ALABAMA.

DOOR-SUPPORT.

1,334,442.

Specification of Letters Patent. Patented Mar. 23, 1920.

Application filed July 23, 1919. Serial No. 312,740.

To all whom it may concern:

Be it known that I, LOUIS T. EANES, a citizen of the United States, residing at Selma, in the county of Dallas and State of Alabama, have invented certain new and useful Improvements in Door-Supports, of which the following is a specification, reference being had to the accompanying drawings.

10 This invention relates to an improved door support, and as one of the objects of the invention, it is the aim to provide a device of this kind, which is simple, efficient and practical in construction, and may be manufactured for a relatively low cost and sold at a reasonable profit.

It is well known that doors or the like depending simply upon hinges for support, in time sag, and therefore drag or scrape on the sill, particularly at the outer lower portion of the lower edge of the door. Hence, as a further object of the invention, it is the aim to provide an improved door support, which hingedly connects to the upper part 25 of the frame of the door axially with the hinge of the door, and is connected to the door, thereby preventing sagging, and consequently the dragging of the lower edge of the door on the sill.

30 By means of this support, it is obvious that the door will not in time bind upon the sill, but to the contrary will completely close.

A further object of the invention is the provision of a door support consisting of a single length of heavy rod or wire material, bent to form an irregular loop and having its arms secured to the door and provided with a vertical straight portion, which axially aligns with the hinge of the door and 40 is hingedly connected to the frame of the door, thereby supporting the door, in fact reinforcing the door and preventing the same from sagging, whether in closed or open positions.

45 A further object of the invention is the provision of a plate secured on the frame of the door for the reception of the vertical straight portion of the loop, and provided with means on one end of the plate, to be engaged by a part of the loop, to additionally support the door, in fact, to impart a slight lifting action to the door as it completely closes, thereby preventing the door from sagging and dragging upon the sill.

55 While the design and construction at pres-

ent illustrated and set forth is deemed preferable, it is obvious that as a result of a reduction of the invention to a more practical form for commercial purposes, the invention may be susceptible to changes, and the right 60 to these changes is claimed, provided they are comprehended within the scope of what is claimed.

The invention comprises further features and combination of parts, as will be herein-after set forth, shown in the drawings and claimed.

In the drawings:

Figure 1 is a perspective view of a portion of a door frame and a hinged door mounted therein, and illustrating the improved door support applied.

Fig. 2 is a perspective view showing the door open, and illustrating the support.

Fig. 3 is an enlarged detail view of the support detached.

Referring to the drawings, 1 designates the door frame, to which a conventional form of door 2 is hingedly connected by means of the upper door hinge 3.

The door support is constructed from a single length of heavy rod or wire material, bent to form an irregular loop 4, such as that illustrated. This loop has one of its arms 5 provided with an angular portion 6, 85 which terminates in an eye 7, for the reception of the screw, bolt or the like 8, to secure said arm to the panel 10 of the door. The arm having the angular portion is provided with a vertical straight part 11, which 90 is mounted in a bearing 12 of a plate 13. This plate 13 comprises a body portion 14 having one end rolled or over-turned, to form a vertical bearing. The plate is secured by screws or bolts 15 to the frame of 95 the door. The other end of the plate at its upper corner is provided with a laterally extending inclined projection 16. The other arm 5 comprises a horizontal portion 17 and an angularly extending portion 18, which is 100 disposed at an obtuse angle to the horizontal portion. At the point where the portion 18 extends from the horizontal portion 17, said portion 18 cams or rides over the projection 16, which is inclined correspondingly to the 105 portion 18, acting as a reinforcement or support, and to so tension on the portion 18, as to cause the portion 18 to impart a pulling or raising action on the door, particularly as the door reaches its closed position, hence 110

preventing the door from sagging and particularly from dragging upon the sill of the door frame. The lower outer end of the portion 18 terminates in an eye 19, which receives a screw, bolt or the like 20, thereby securely connecting the portion 18 and panel 21 of the door. When the door is opened or closed, the support acts to support and reinforce the door, so as to prevent sagging of the outer portion of the door, which will avoid the lower edge of the door from dragging upon the sill.

The invention having been set forth, what is claimed as new and useful is:

- 15 1. In a closure support, the combination with a frame, of a closure hingedly mounted therein, a support comprising a looped member having arms, one secured to the closure in closed position to its hinged end, the other being fastened to the closure adjacent the free end thereof, said looped member having a straight portion axially alined with the hinge of the closure, a bearing carried by the door frame axially alined with the hinge 25 of the closure and adapted to receive the straight portion of the looped member.
- 20 2. In a door support, the combination with a frame, of a door hingedly mounted therein, a support comprising a looped member having arms secured to one face of the door, said looped member having a vertical straight portion, and a bearing carried by the door frame axially alined with the hinge 30 of the door and adapted to receive a vertical straight portion of the loop, said bearing having a plate, one end of which being

provided with a lateral inclined projection, the upper part of the supporting loop having a horizontal part and an inclined part, the former of which being disposed in parallel with the upper edge of the plate, and the latter of which adapted to cam or ride upon the lateral projection, hence supporting and reinforcing the inclined part of the loop and preventing sagging of the door. 40 45

3. In a door support, the combination with a door frame and a door hingedly mounted therein, of a plate secured to the top part of the frame, one end of said plate having a lateral projection inclined downwardly, the other end of the plate having a vertical bearing axially alined with the hinge of the door, a door supporting loop comprising a pair of arms securely connected to the door, one of the arms of the loop 50 having a vertical straight portion engaging said vertical bearing, the lower end of the support having a horizontal portion in parallel with the upper edge of the plate, the other arm of the supporting loop being inclined downwardly and laterally from said horizontal portion and adapted to ride or cam upon said projection, for reinforcing the loop and preventing the door from sagging. 55 60 65

In testimony whereof I hereunto affix my signature in the presence of two witnesses.

LOUIS T. EANKS.
